By Attorneys

UNITED STATES PATENT OFFICE.

ALBERT Y. EDWARDS, OF SPRINGFIELD, OHIO, ASSIGNOR TO THE FOOS GAS ENGINE COMPANY, OF SPRINGFIELD, OHIO, A CORPORATION OF OHIO.

DESIGN FOR AN INTERNAL-COMBUSTION ENGINE.

51,524.

Specification for Design.

Patented Nov. 27, 1917.

Application filed September 4, 1917. Serial No. 189,702. Term of patent 7 years.

To all whom it may concern:

Be it known that I, ALBERT Y. EDWARDS, a citizen of the United States, residing at Springfield, in the county of Clark and State of Ohio, have invented a new, original, and ornamental Design for Internal-Combustion Engines, of which the following is a specification, reference being had to the accompanying drawings, forming part thereof.

Figure 1 is a side elevation and Fig. 2 a top plan of an internal combustion engine, showing my new design.

I claim:

The ornamental design for an internal combustion engine, as shown.

ALBERT Y. EDWARDS.

Witnesses:

CHAS. I. WELCH,
ALICE M. BENSON.
